UNITED STATES PATENT OFFICE

ALRAH B. EDWARDS, OF ABILENE, TEXAS

EATING INSTRUMENT COMPACT

Application filed April 26, 1928. Serial No. 273,027.

This invention relates to eating instruments and has for its object to provide a novel compact comprising a fork, a knife, and a spoon in selected combinations and 5 adapted for use by campers, picnickers, soldiers, boy scouts, and others; and which may be safely carried in the side pockets of automobiles, in the pockets or belt of a person, and in other places where ordinary 10 eating instruments can not be safely carried.

Another object of the invention is to provide an eating instrument compact comprising a plurality of eating instruments made of sheet metal and shaped to telescope one 15 within the other into a small, convenient and secure compact, which can be easily packed or stored, and transported.

Another object of the invention is to provide a compact combining two eating instruments each having a handle and a working 20 part, the working parts adapted to telescope in the handles, and the handles having open outer ends to receive extension handles whereby the instruments may be used for 25 roasting or broiling purposes, or wherever a long handled instrument is useful or desirable.

And a further object of the invention is to provide a compact comprising a pair of 30 eating instruments each having a working part adapted to telescope within the handle of the other part, and an additional instrument formed in one or both of the handles.

The accompanying drawings illustrate a 35 selected embodiment of the invention and the views are as follows:

Fig. 1 is a plan view of the compact.

Fig. 2 is a plan view of one of the instruments.

Fig. 3 is a plan view of another instrument partly in section.

Fig. 4 is a longitudinal sectional view on the line 4—4 of Fig. 1.

Figs. 5 and 6 are transverse sectional 45 views on the lines 5—5 and 6—6 of Fig. 4.

Fig. 7 is a longitudinal sectional view of the compact shown in Fig. 8.

Fig. 8 is a plan view showing a modification.

Referring to the drawings, and particu-

larly to Figs. 1 to 6 inclusive, 10 designates a knife having a handle 11, and a blade 12 which is preferably made of sheet metal integral with the handle. The blade is offset at 13 to provide a shoulder against which the handle of a companion instrument abuts when the two instruments are telescoped. 55 A fork 14 having a prong member 15 and a hollow handle 16 is preferably made of sheet metal in one piece, and the prong member 15 is offset from the handle to form a shoulder 17 against which the knife handle 11 abuts when the knife and fork are telescoped, Fig. 4. The prong member is bowed, as at 18, Fig. 4, which is usual with 60 the ordinary type of fork.

The knife and fork are each made from a single piece of sheet metal, the handles being in tubular form with the edges of the metal abutting at one side 19. The outer 70 end of the handle may be left open, at 20, to allow an extension handle or other object 21 to be inserted therein for roasting or broiling purposes, or wherever a long handled instrument is useful or desirable. The inner end of the handle, where it joins the prong member or blade, is open, at 22. This construction allows the members to be 75 thoroughly washed and cleaned and permits circulation of air through both of the members when they are telescoped, thereby providing a sanitary eating compact.

In Figs. 7 and 8 I have shown the handle of one instrument indented at its outer end as indicated at 23 and curved on its opposite side as at 24 to provide the spoon 25. This end of the handle may also be spread or bulged outwardly at each side, as at 26, to provide a spoon wider than the handle of the other member. 80

In this manner I am able to provide three members incorporated into two single pieces which may be telescoped and easily carried about as a single unit. By offsetting and shouldering the instruments as shown and described, I am able to provide the fork with an arch like ordinary forks, which is 95 desirable, and this is accomplished without enlarging the handle designed to receive the prong member. 100

I have provided a compact of small size and convenient shape and comprising two or more eating instruments, which can be easily and safely carried or packed for storage or shipment. The parts of the compact are securely telescoped so that they will not rattle while being transported. The sharp parts of the instruments are wholly protected within the handles so that they will not be damaged or cause damage when not in use. The construction is of particular importance because it permits water to circulate through the handle and about all parts of the instruments to enable them to be thoroughly cleansed, and when the instruments are telescoped air may circulate through the compact to keep it in a fresh and sanitary condition.

I am aware that changes may be made in the form, construction and arrangement of the parts without departing from the scope or spirit of the invention, and I reserve the right to make all such changes as fairly fall within the scope of the following claims:

I claim:

1. An eating instrument compact comprising an instrument having a handle indented at its outer end and curved on its opposite side to provide a spoon bowl, and a handle carrying an instrument with a bowed termination, the first named instrument being receivable within the handle of the last-named instrument, with the bowed termination nesting within the handle of the first named instrument in opposed relation to the curvature of the spoon.

2. An eating instrument compact comprising an instrument having a handle indented at its outer end and curved on its opposite side to provide a spoon bowl, and a handle carrying an instrument with a bowed termination, the first-named instrument being receivable within the handle of the last-named instrument, with the bowed termination nesting within the handle of the first-named instrument in opposed relation to the curvature of the spoon, the handles being provided with oppositely-disposed offsets and shoulders.

50 ALRAH B. EDWARDS.
